J. NEWKIRK.

Lime Kiln.

No. 18,764.

Patented Dec. 1, 1857.

UNITED STATES PATENT OFFICE.

JACOB NEWKIRK, OF FACTORYVILLE, NEW YORK.

LIMEKILN.

Specification of Letters Patent No. 18,764, dated December 1, 1857.

To all whom it may concern:

Be it known that I, JACOB NEWKIRK, of Factoryville, in the county of Tioga and State of New York, have invented certain 5 new and useful Improvements in Limekilns; and I do hereby declare the following to be a full, clear, and exact description of the same, reference being had to the accompanying drawings, in which—

10 Figure 1 represents a perspective view of the kiln complete. Fig. 2 represents a perspective view of a section through the kiln, the boilers being entirely removed.

Similar letters of reference where they 15 occur in the separate figures, denote like parts of the kiln in both.

The nature of my invention relates to the peculiar manner of carrying up of the flame and heat into the arch and thence by cross 20 flues into the kiln or stack.

To enable others skilled in the art to make and use my invention, I will proceed to describe the same with reference to the drawings.

25 A, represents the exterior of the stack or kiln, which may be built in the usual well known manner.

B, Fig. 2, represents the interior of the kiln. The kiln at its base, in the interior, is 30 divided into two compartments, by the wedge shaped arch C as I term it, which contracts the area of the inside of the kiln at the base very considerably, holding the limestone not sufficiently burned, just where the 35 fire is most intense, and directing it toward two draw holes or openings, at the sides or back of the kiln as may be preferred.

D, represents the fire chamber, located in the center of the base of the arch C. It is 40 furnished with a grate a, which may be in sections and removable, so as to be replaced by new ones when the old ones are burned out, without stopping the fires. Underneath the fire chamber is the ash pit E.

45 From the fire chamber direct there are a series of flues c, c leading into the divided parts B' B', of the kiln. These flues are deeper next the kiln than next the fire chamber, for the purpose of directing the flame 50 and heat downward, or toward that part of the limestone lying immediately on the grates or bars b, b. These grate bars b, are not always necessary, for at times the kiln will burn with such regularity that there is 55 no necessity of stopping the regular dropping down of the lime. But there are peri-

ods when these grates, or the introduction of bars, are actually necessary, and to suit both emergencies the grate, or bars are made sectional, and easy removable as circumstances may require. Through the crown of the fire chamber another fire flue e leads up into the arch C, and from this flue e, there leads a series of cross flues i into the apartments B' B'. The object of carrying this 60 second set of fire flues up into the arch is twofold, first, to bring portions of the heat higher up into the limestone, which insures more equable burning, and secondly to heat up the arch itself to prevent anything like a 65 chill or slack heat around it.

The grates or bars b, as above stated, are sometimes dispensed with, and to easily insert or withdraw them, openings n, n are made through walls of the kiln. Underneath these grates, or the point at which they are placed, are inclined planes E, E, onto which the burned lime falls, and by which it is directed to the draw holes F, F, at the exterior of the kiln. These planes and draw 70 holes are represented at the sides of the kiln or the fire chamber. They may be inclined toward the back of the kiln; and when the kiln stands on a level surface, I so 75 contemplate placing them. When the kiln is set into a bank then the side delivery may be the most convenient, but in both cases I use the planes for directing the lime to the exterior of the kiln without the trouble of drawing it out by hand.

80 The limestone, and fuel, are fed in at m, m, Fig. 1, and slides G, G, are made to cover these openings when requisite.

H, H, H, are steam boilers, encased by outer walls or shells I, I, I, and so located, 85 and controlled by slides or cut-offs o, o, o, &c., as that they may receive heat from the kiln under and around them, each having its special flue J, J. Or when the kiln is not fired, and steam is desired for working the 90 engine for hoisting the charge or for other purposes, each or either of said boilers may be heated up by its own individual fire place r, r.

95 s (one only being seen) are hinged doors 105 for enlarging the feed openings m. And when the boilers are not required, and the flues leading under and around them are closed, then the waste heat, gas, &c., escapes through m.

100 K, is a frame of wood or iron, externally placed around the stack or kiln for strength-

ening it against the action of the internal heat.

The kiln may be furnished with the usual "peep holes," or openings through the walls, for stirring up the mass within to prevent it from clogging or choking; and the arch C, is made to project over the fire flues c, i, to prevent them from being choked, as seen at u, u, &c.

10 The placing of the boiler over the top of the kiln, together with the slides G, regulates and confines the heat within the kiln. It also makes a better draft through the kiln upon the same principle that a stove 15 will draw better when it has a contracted exit flue than if the whole top of the fire chamber were open.

Having thus fully described the nature

and object of my invention, what I claim therein as new, and desire to secure by Letters Patent is—

Instead of taking the upper fire flues directly from the fire chamber, into the interior of the kiln, the carrying a portion of the flame and heat up into the arch, and thence 25 by the upper flues into the stack or interior of the kiln, by which means I economize and make a better distribution of the heat and better draft than when it is taken alone and immediately from the fire chamber as set 30 forth.

JACOB NEWKIRK.
